UNITED STATES PATENT OFFICE.

HENRY ZIMMERMAN, OF ROULEAU, SASKATCHEWAN, CANADA.

STIRRUP.

1,219,525.

Specification of Letters Patent. Patented Mar. 20, 1917.

Application filed June 21, 1916. Serial No. 105,039.

To all whom it may concern:

Be it known that I, HENRY ZIMMERMAN, a citizen of the United States, residing at Rouleau, in the Province of Saskatchewan and 5 Dominion of Canada, have invented certain new and useful Improvements in Stirrups, of which the following is a specification.

This invention relates to improvements in stirrups and more particularly to a safety 10 stirrup and its object primarily is to produce a stirrup from which the rider may readily extricate his feet and so avoid the possibility of painful or fatal accident should he be thrown from his mount; or in 15 case of a run-a-way, etc. More specifically the invention contemplates the manufacture of a stirrup having a hinged foot plate one end of which may be released from operative position by an upward, down- 20 ward or transverse movement of a release lever thereby enabling the rider to operate the lever with little forethought. With the foregoing and other objects in view the invention consists in the combination and ar- 25 rangement of parts to be hereinafter fully described in this specification, pointed out in the appended claims and illustrated in the accompanying drawings which form a part of said specification and in which—

30 Figure 1 is a front view of a stirrup constructed in accordance with my present invention.

Fig. 2 is an enlarged fragmentary view of the same.

35 Fig. 3 is a section taken on line 3—3 of Fig. 1.

Fig. 4 is a top plan view of the device.

Like reference characters denote corresponding parts throughout the several views.

40 My stirrup comprises the side plates 1, 2 connected by the top bar 3 that is supported by the stirrup leather 4. The side plates diverge from the bar 3 to the foot plate 5 which is connected by hinge 6 to the plate 1. 45 The side plate 1 carries a pin 7 whereon a link 8 is pivotally supported and said link is connected by the foot bar 9 with the pitman 10 which is formed with an elongated slot 11 that receives the stop pin 12 carried 50 by the plate 2. The lower end of the pitman 10 is disposed opposite the mouth of a recess 13, formed in the plate 2, and carries a pin 14 disposed in that recess, the inner end of 55 said pin being connected to a link 15 which is disposed in a channel 16 that communicates with the recess 13 and with a lower re- 60 cess 17 the mouth of which opens upon the side of plate 2 away from the mouth of the recess 13. A pin 18 is disposed in the recess 17 and serves as a rest for the lower end 65 of the link 15 and is formed with a collar 19 of greater diameter than that recess and with an integral collar 20 of smaller diameter than that recess and disposed within the 70 same. An expansion spring 21 is arranged upon the pin 18 with one end abutting a hinge 22 and the other secured to the said collar 20. The pivoted leaf of hinge 22 is normally disposed in a slot 23 formed in the plate 2 and is supported upon the inner end 75 of the said pin 18; the said hinge 22 being secured to the foot plate 5 to normally retain the same in operative engagement with the plate 2.

In Fig. 1, full lines the stirrup is shown in 75 operative position. The rider rests his foot upon the foot plate 5. To open the stirrup the foot plate 5 is dropped to open or inoperative position, shown in dotted lines. To perform this operation the rider may raise 80 his foot against the bar 9 thus raising the link 15 off the pin 18 and out of engagement with the collar 20 and permitting the spring 21 to eject the pin 18. Withdrawal of the pin 18 will withdraw the support of the 85 hinge 22 and permit the same, together with the foot plate 5, to drop into open position and so release the rider's foot. Should the rider move the bar 9 transversely he will also disengage the link 15 and pin 18, or 90 should he depress the bar by hand he will force the link 15 off the pin 18 and, in any event, release it from engagement with the said pin 18 and collar 20. It is obvious that many minor changes and alterations may be 95 made in the form and construction of the invention without in any way departing from the spirit of the invention. It is not therefore desired to confine the invention to the precise form herein shown, but it is intended to include all such as come properly 100 within the scope claimed.

What is claimed is:—

1. In a stirrup, side plates, one of which is formed with upper and lower recesses and with an upper channel connecting said recesses and a lower channel leading from the lower recess to the end of the plate, a top bar connecting said side plates, a foot plate hinged to one of said side plates, a link pivotally carried by said side plate, a pitman carried by the opposite side plate and movable 110

longitudinally thereof in a limited degree, a bar connecting said link and pitman; a link disposed in the upper channeled portion of said last named side plate, a hinge carried by 5 said foot plate and normally disposed in the lower channeled portion of said side plate, a pin disposed in the lower recessed portion of said side plate and normally connecting said hinge and link, a connection between 10 said link and the said pitman through the medium of said upper recess, a collar slideable upon the last named pin and normally in engagement with the last named link and a spring encircling said last named pin and 15 said collar.

2. In a stirrup, side plates, one of which is formed with upper and lower recesses and with an upper channel connecting said recesses and a lower channel leading from the lower 20 recess to the end of the plate, a top bar connecting said side plates, a foot plate hinged to one of said side plates, a link pivotally carried by said side plate, a link disposed in the upper channeled portion of the other

side plate, a hinge carried by said foot plate 25 and normally disposed in the lower channeled portion of said last named side plate, a pin disposed in the lower recessed portion of said last named side plate and normally connecting said hinge and the last named 30 link, means carried by said pin for moving the same, with relation to its side plate, when disengaged from the last named link, and manually operable or foot-controlled means connecting the first and last named links and 35 partly disposed in said upper recess whereby relative movement of the latter may be effected to disengage the same from the said pin.

In testimony that I claim the foregoing 40 as my own I have hereto affixed my signature in the presence of two subscribing witnesses.

HENRY ZIMMERMAN.
